UNITED STATES PATENT OFFICE.

WILLIAM J. WARREN, OF YUBA CITY, CALIFORNIA, ASSIGNOR OF ONE-HALF TO CHARLES L. WILBUR, OF YUBA CITY, CALIFORNIA.

REINFORCED-CONCRETE CONSTRUCTION.

No. 918,231.

Specification of Letters Patent.

Patented April 13, 1909.

Application filed March 14, 1908. Serial No. 421,170.

To all whom it may concern:

Be it known that I, WILLIAM J. WARREN, a citizen of the United States, residing at Yuba City, in the county of Sutter and State 5 of California, have invented new and useful Improvements in Reinforced-Concrete Construction, of which the following is a specification.

My invention relates to a reinforced concrete construction, and pertains especially to an improved reinforced hollow concrete wall for buildings.

The object of the invention is to provide a monolithic structure of concrete, which shall 15 have air spaces or flues, or be otherwise made hollow a great part, which shall be of much lighter weight than the ordinary, solid concrete walls, and which will accordingly require less expensive foundations; yet at the same time will possess all the attributes of 20 strength, rigidity and permanence.

The invention consists of the parts and the construction and combination of parts as hereinafter more fully described and claimed, 25 having reference to the accompanying drawings, in which—

Figure 1 is a perspective view showing the wall construction especially adapted for heavy walls and large buildings. Fig. 2 is a 30 similar view, showing my wall construction adapted for lighter buildings.

In practice, the invention may take either of two forms, as shown in the drawings; one of these forms, represented by Fig. 1, being 35 especially adapted for heavy walls and large buildings, and the form or type represented in Fig. 2, being particularly adapted for dwellings and smaller buildings where a reinforced structure is desired, but where lightness and cheapness are important features.

By reference to Fig. 1, A represents my improved wall construction of concrete having the vertical reinforcing rods 2, the horizontal reinforcing rods 3, the cross-stays 4, 45 and the vertical flues or hollow spaces 5. In the construction of this wall I use a core form 6, as shown in Fig. 1, for the purpose of forming the flues 5; and in the wall construction I employ panels 7, movable supports 8, 50 and connecting bolts 9, and proceed in the following manner: The panels 7 are each about eighteen inches high, and cut to any required length. They are held in position by the movable supports 8, which latter are 55 made of two pieces of lumber 1" x 4" x 4"

nailed together with a piece $\frac{1}{2}$ " x 2" x 4" between them at each end, thereby leaving a half inch slot for the bolt 9 to operate in.

After the footings are in place, and the building of the wall is to begin, two panels 60 are placed on the footings opposite each other around the entire building, being held the required distance apart by suitable spacing blocks or pieces, not here shown. The movable supports 8 are placed the requisite distance apart to hold the panels in position. After the latter are set up on the footings and 65 suitably supported, the core forms 6 are placed between the panels at the required distances apart, corresponding with the desired spacing 70 of the vertical flues 5. These core forms are preferably made in the manner shown, of galvanized iron, with a couple of hand-holds 6^a at each side to permit of their being easily removed. The inside of the core forms 6 are 75 then filled with damp sand, and the space around them filled and tamped with concrete. As the work progresses the core forms are pulled up, leaving the sand, which 80 prevents the concrete from filling the hollow until it has had time to set.

When the first set of panels has been filled around the building, the movable supports 8 are raised, the lower panel released and placed above the remaining 85 panel between the supports, appropriate spreaders inserted, and then bolted in position, to form a trough or bench in which the concrete is dumped and tamped around the core forms, as described in the first instance. 90 Every time a fill is made around the building, or to any desired length of the wall, the same process of raising and resetting the panels is repeated, until the wall or column is carried up the required height. Each time the 95 cores are lifted they are again filled with sand, so that when the whole wall is completed there will be a series of columns of sand in each flue 5. These sand cores or columns may be removed after the building 100 is up, by means of holes 10, Fig. 1, left in the inside wall at suitable intervals. In rearing the wall, these holes may be formed by placing two vertical pieces of thin board or tin 7' between the core form 6 and the inside 105 panel 7 (as the work of filling is going on) with a suitable packing of sand between these boards; the boards being drawn upward and used over and over again, as the work progresses, leaving the openings 10 110

communicating with the flues 5. Later, the sand cores may be washed out with a hose passed in through the holes 10. This sand may then be gathered up and used for 5 plastering; hence there will be no waste of material.

During the upbuilding of the wall, the horizontal reinforcing rods 3 are laid in at suitable intervals, and arranged on each 10 side of the flues 5, as clearly shown in Fig. 1. These horizontal reinforcing members 3 are connected at suitable intervals and between the flues 5 by the reinforcing stays 4. In addition to this, the vertical reinforcing 15 bars 2 are used, preferably a set of these vertical reinforcing bars being employed on each side of the flues 5, as shown in Fig. 1. A wall of this structure can be made of any desired thickness, with hollows to 20 correspond, by simply regulating the size of the core forms and the length of the sticks or spreaders used between the panels. A wall of this construction is light and strong, and has the advantage of a hollow 25 monolithic structure with air spaces, making the walls warm in cold weather and cool in hot weather, and proof against moisture. This structure is obtained entirely without the use of expensive hollow tiles. These 30 walls being hollow, and comparatively light, require a less foundation; and consequently, there is a saving of material and expense 35 over the ordinary solid reinforced systems commonly in use.

In Fig. 2, I have shown a structure 40 adapted for lighter buildings, in which I use practically only a single wall with reinforcing ribs, instead of a double wall, as in Fig. 1, with connecting ribs. Thus, as seen in Fig. 2, A' represents the wall, with the laterally-extending reinforcing ribs a, these ribs 45 running both horizontally and vertically, as shown in Fig. 2, and separated by wedge-shaped pockets or hollow spaces 5'. In this structure I use the same system of vertical reinforcing bars 2', the double set of 50 horizontal reinforcing bars 3', and the connecting stays 4'. The method of procedure in building this wall is substantially the same, as far as the use of the panels 7, etc., is concerned, except that instead of using core forms, as 6, I employ a wedge-shaped core 6', Fig. 2, which latter cores are laid in 55 against the inside of the inside panels, and the concrete packed in around these wedges. After the wall is set, and the panels removed, the wedges are readily removed.

The reinforced concrete ribs or webs a' are arranged, in practice, about sixteen inches

apart, and at the crossing of these webs at the 60 time the wall is going up, are inserted dovetailed blocks 11, which remain embedded in the finished wall, and permit the furring strips to be nailed thereto. The laths are then nailed to these furring strips, and when the plaster 65 is put on the hollow spaces in the wall are enclosed. If desired, these hollow spaces 5' may be connected in either vertical or horizontal series, as indicated at 13, by the use of a wedge-shaped piece of wood placed in proper 70 position between any two adjacent wedges 6' as the wall is being built. When the wedges 6' are removed, these connecting wedges may be knocked out, leaving the flues connecting the pockets 5'. In this way I get a hollow reinforced concrete wall with vertical flues, just 75 as I do in Fig. 1. This wall can also be made any desired thickness, and the hollows behind the plaster may be regulated in size and depth to meet requirements. 80

Having thus described my invention, what I claim and desire to secure by Letters Patent is—

1. The method of concrete construction, which includes building up a concrete wall 85 between movable side panels, and forming hollow spaces in the wall by placing therein hollow open ended core forms, filling these core forms with sand, raising these core forms and maintaining them filled with sand, 90 leaving the sand in the wall while the construction of the same proceeds, placing vertical spaced pieces in the wall between the core wall and the side panels as the wall progresses, and placing a packing of sand between 95 said pieces, to form side openings which connect with the vertical spaces and subsequently removing the sand through said side openings in the wall.

2. The method of reinforced concrete construction, which comprises the building up of a wall between suitable side inclosures, and simultaneously with the building up of the wall placing hollow core forms in the wall and also placing spaced pieces in the wall 100 between said core forms and the outside of said wall and filling them with sand, raising these core forms and spaced pieces as the building of the wall progresses upward and maintaining them filled with sand, and leaving the sand in the wall. 105

In testimony whereof I have hereunto set my hand in presence of two subscribing witnesses.
